BELT

Richard F. Ballou, 8391 Quigby St.,
Westminster, Colo. 80030

Filed Feb. 18, 1972, Ser. No. 227,702

Term of patent 3½ years

Int. Cl. D2—07

U.S. Cl. D2—380

FIG. 1 is a perspective view of a belt showing my new design;

FIG. 2 is a top plan view thereof shown broken away for convenience of illustration;

FIG. 3 is an edge view thereof; and

FIG. 4 is a bottom plan view.

I claim:

The ornamental design for a belt, as shown and described.
